US00D682343S

(12) **United States Design Patent**
Waters

(10) **Patent No.:** **US D682,343 S0**
(45) **Date of Patent:** **** May 14, 2013**

(54) **LIGHTED GLASSES**

(76) Inventor: **Michael Waters**, Aspen, CO (US)

(**) Term: **14 Years**

(21) Appl. No.: **29/409,506**

(22) Filed: **Dec. 23, 2011**

(51) LOC (9) Cl. **16-06**

(52) U.S. Cl.

USPC **D16/309**; D16/325

(58) **Field of Classification Search**

USPC D16/101, 300-342, 900; D29/109-110;
D24/110.2; 351/41, 44, 51-52, 62, 158, 92,

(57) **CLAIM**

I claim the ornamental design for lighted glasses, as shown and described.

DESCRIPTION

FIG. 1 is a perspective view of the lighted eyeglasses according to my new design;

FIG. 2 is a front elevational view of the lighted eyeglasses of FIG. 1;

FIG. 3 is a rear elevational view of the lighted eyeglasses of FIG. 1;

FIG. 4 is a top plan view of the lighted eyeglasses of FIG. 1; FIG. 5 is a bottom plan view of the lighted eyeglasses of FIG. 1;

FIG. 6 is a left side elevational view of the lighted eyeglasses of FIG. 1; and,

FIG. 7 is a right side elevational view of the lighted eyeglasses of FIG. 1.

1 Claim, 5 Drawing Sheets
